[57] CLAIM

The ornamental design for a sandwich roll, as shown
and described.

DESCRIPTION

FIG. 1 is a top plan view of a sandwich roll showing my
new design;

FIG. 2 is a front elevational view showing the two
halves separated;

FIG. 3 is an elevational view looking from the upper
right corner of FIG. 1 with the two halves separated;
FIG. 4 is an elevational view looking from the right of
FIG. 2;

FIG. 5 is an elevational view looking from the left of
FIG. 2; and

FIG. 6 is a bottom plan view.
